DRYER FOR BATHING SUITS

Charles E. Jennings, Jr., 4020 Simon Road,
Youngstown, Ohio

Continuation of applications Ser. Nos. 66,326 and 66,327,
Aug. 14, 1961. This application May 3, 1962, Ser. No.
70,429

Term of patent 14 years

(Cl. D49—1)

FIG.1

FIG.2

FIG.3

FIG. 4

FIG. 5

FIG. 6

FIGURE 1 is a perspective view of a dryer for bathing suits, showing my new design;

FIGURE 2 is a front elevational view thereof;

FIGURE 3 is an end elevational view thereof;

The rear and side not shown are like the respective front and side shown except that the dial is omitted.

FIGURE 4 is a perspective view of a modified form of a dryer for bathing suits;

FIGURE 5 is a front elevational view of the modified form thereof;

FIGURE 6 is an end elevational view of the modified form thereof.

The rear and side of the modification not shown are like the respective front and side shown except that the dial is omitted.

This application is a continuation of my copending applications Serial Nos. D. 66,326 and D. 66,327 filed August 14, 1961, now abandoned.

I claim:

The ornamental design for a dryer for bathing suits, as shown and described.
